UNITED STATES PATENT OFFICE.

EDWIN F. MOWER, OF BOSTON, MASSACHUSETTS.

FAIR-STITCH MACHINE.

SPECIFICATION forming part of Letters Patent No. 684,548, dated October 15, 1901.

Application filed July 3, 1900. Serial No. 22,439. (No model.)

To all whom it may concern:

Be it known that I, EDWIN F. MOWER, of Boston, in the county of Suffolk and State of Massachusetts, have invented a new and useful Improvement in Fair-Stitch Machines, of which the following, taken in connection with the accompanying drawings, is a specification.

My invention relates to a peculiar mechanism for forming a stitch of a class that is usually termed the "fair-stitch;" and it consists in an arrangement of swinging and tilting parts that together actuate a loop-controller that traverses in such a manner as to effectually hold and control the movements of that part of the thread that forms the loop that is eventually drawn into the sole, where it constitutes that part of the stitch that serves to hold the sole in place when the stitch is completed.

My invention and the machine of which it forms a part are illustrated in the accompanying drawings, in which—

Figure 1 is a view of my machine in side elevation, parts being shown in vertical section. Fig. 2 is a vertical longitudinal section of the machine, showing parts in elevation. Fig. 3 is a front elevation, parts being represented as cut away for the purpose of illustrating the construction. Fig. 4 is a plan, a part of casing cut away. Fig. 5 is a plan showing details of lower mechanism. Figs. 6 to 12 are sketches to illustrate the method of forming the stitch. Figs. 13 and 14 are elevations showing the loop-controller and its connected parts.

In the drawings a complete fair-stitch machine is shown, but only for the purpose of illustrating more clearly the working of the parts in which my invention is involved.

The base of the machine is indicated by A and the front head by A'. The main shaft B has upon it a hand-wheel B', rigidly connected, and a loosely-running belt-wheel B², which has a friction-clutch connection at B³ with the hand-wheel B'. The belt clutch-wheel B² slides freely on the shaft B, so as to be thrown into or out of connection with the clutch-bearings at B³. For moving the wheel B² into clutch connection the following-described device is used, Fig. 2: A beveled wheel B⁴ is attached to the shaft B and a similar one B⁵ to the belt clutch-wheel B². A

double beveled wheel B⁶ is mounted on a vertically-moving rod B⁸ by an axle-pin B⁷. The rod B⁸ slides in the bracket-piece B⁹ and is 55 operated by the bent lever B¹⁰, which is connected to it by a pivot-joint B¹¹ and swings on a fulcrum-pin B¹² on the arm A². A link B¹³ serves to connect the bent lever B¹⁰ to an operating-treadle. (Not shown.) It is obvious that by forcing the wheel B⁶ upward the belt clutch-wheel B² will be thrown into working connection with the hand-wheel B', and thus start the machine.

The needle and awl bars are driven by the 65 disk C, Fig. 2, on the main shaft B. This disk C has two crank-pins mounted upon it in the usual manner of the double-crank-pin disk. A pitman C² connects one of the crank-pins to the awl-bar D and the pitman C² connects the other crank-pin to the needle-bar E. By the simple arrangement of two crank-pins diametrically opposite upon the same disk for operating the needle E' and awl D' the time of the movement of said needle and awl is always correct—that is, one goes up when the other is going down.

A feed movement is given to the awl and needle by a mechanism that may be explained as follows: Both the needle and awl bars E and D are mounted in the swinging head N, Figs. 2 and 3. This swinging head is pivotally held at its upper end by the screw N' and at its lower end by a screw N², Fig. 2, which works in a slot made in the fixed head A', so 80 that the lower end of it may swing back and forth, and thus give a feeding action to the awl and a corresponding movement to the needle. The feed motion is given to the swing-head N by the groove-cam F', Figs. 1 and 2. This cam operates a lever F², pivoted on the fixed stud A⁵, which communicates motion through an adjustable fulcrum F⁴ to rocker-arm F³ on the rocker-shaft F, Fig. 1. A second arm F⁶ on the said rocker-shaft is 85 connected by a link F⁷ and pivot F⁸ to the lower end of the swinging head N and gives motion to the same.

The peculiarly novel part of this machine is in the loop-controller device, shown immediately under the work-supporting plate M. The loop-controller proper is indicated by H¹⁰ and has four motions—that is, a forth-and-back motion nearly horizontally in the

direction of the dotted arc $k k'$ and an up-and-down motion nearly vertical in the direction of the dotted arc $h h'$, Fig. 2. These motions are given to the loop-controller H^{10} by the eccentric H and cam K . (See Figs. 1 and 2.) The eccentric H works through the link H' , pivot-pin H^2 , lever $H^3 H^5$, which swings on the fulcrum H^4 , link H^6 , and pivot-joint H^7 and loop-controller lever H^9 , which tilts on a moving fulcrum H^8 and causes the loop-controller H^{10} to move toward or away in a vertical arc from the stock W or in the general direction of the dotted arc $h h'$. The other motions—namely, the nearly horizontal ones—
15 are imparted by the eccentric K , working through the link K' , pivot-pin K^2 , lever K^3 , having a fulcrum at K^3 , link K^5 , pivoted at K^4 and K^6 , and bell-crank lever $K^7 K^8$, having a fixed fulcrum at K^9 and connected to the loop-controller lever H^9 at H^8 . The motion thus communicated causes the loop-controller H^{10} to move nearly horizontally in the direction of the dotted arc $k k'$.

In addition to the ordinary presser-foot P
25 an additional laterally-adjustable stitch-holder G is used. It is attached to the presser-foot bar P' by screws $G' G'$.

The method of forming the stitch is illustrated in Figs. 6 to 12, inclusive. Figs. 6 and
30 7 show the starting positions. In Fig. 8 the thread is shown as carried by the needle E' just through the stock W . For convenience in describing the formation of the stitch we assume that one has been made as illustrated
35 in Fig. 7. The needle in the first part of its

upward motion will cause a loop to form, as shown in Fig. 9. Now the loop-controller H^{10} will take the loop, and as the needle goes upward the loop-controller will follow, but keep the thread taut. (See Fig. 10.) A continued 40 upward movement of the needle and of the loop-controller H^{10} will bring the stitch to the condition shown in Fig. 11, the loop-retainer H^{10} being close up to the work. The loop-retainer is now withdrawn, and the thread is 45 drawn taut, as shown in Fig. 12. The stitch-holder G serves to hold the previously-formed stitch in place.

I claim—

In a fair-stitch machine an awl and mechanism for operating the same; a needle having an eye in the point; means for operating said needle; a stitch-holder adapted to hold a stitch in place while the next one is being formed; means for operating said stitch-holder; a loop-controller adapted to retain the loop while the needle is making its upward stroke and to follow the withdrawing thread, maintaining a steady tension until the fair-stitch is formed, and mechanism for operating the same substantially as and for the purpose set forth.

In testimony whereof I have signed my name to this specification, in the presence of two subscribing witnesses, on this 13th day of 65 June, A. D. 1900.

EDWIN F. MOWER.
